Application January 31, 1938, Serial No. 187,940

10 Claims. (Cl. 179—171)

The present invention relates to amplifiers for radio signalling systems and the like, embodying tuned high frequency signal conveying circuits in connection with the input or grid-to-cathode capacitance of electric discharge amplifier devices and the like.

When such devices, in connection with tuned high frequency circuits, are subjected to gain controlling potentials on the input or control grid, the input capacitance may vary sufficiently to cause a change in the tuning of the circuits connected therewith beyond a desired or permissible limit, and it is an object of the present invention to provide means for preventing such changes in the input capacitance of an electric discharge device in connection with a tuned circuit from changing the tuning thereof.

More particularly, it is an object of the present invention to provide, in connection with a tuned signalling circuit, electric discharge amplifier means wherein changes in input capacitance with changes in biasing potential may be made substantially equal in magnitude and opposite in direction of change, with changes in biasing potential. With this arrangement, automatic volume control potentials may be applied at an electric discharge amplifier, mixer tube or detector in connection with a tuned signalling circuit, without causing changes in capacitance across and variations in tuning of the circuit with variations in the magnitude of the automatic volume control potential.

It may also be considered as a specific object of the present invention, to provide means for compensating for the shift of the resonance frequency of tuned signalling circuits in electric discharge amplifiers tending to result from change in input capacitance of an electric discharge device with varying grid bias potential, more particularly when such circuits operate at high frequencies or high intermediate frequencies and have a high L/C ratio.

It is a still further object of the present invention, to provide in a single electric discharge device, amplifying, mixing or detecting and compensating means for resonant frequency shift of a tuned signalling circuit in connection with an electric discharge device because of input capacitance variation with varying grid voltage.

The invention will, however, be better understood from the following description, when considered in connection with the accompanying drawings, and its scope will be pointed out in the appended claims.

In the drawings,

Figure 1 is a schematic circuit diagram of a portion of an electric signalling system, such as an intermediate frequency amplifier of a superheterodyne receiver, embodying the invention, 5

Figure 2 is a curve showing input capacitance variation of a standard amplifier tube with variation in control grid bias, and

Figure 3 is a schematic circuit diagram, showing a modification of the circuit of Fig. 1, also embodying the invention. 10

Referring to Fig. 1, 5 is an electric discharge device representing an amplifier, signal mixer or detector having input or control grid 6 and a cathode 7 connected with a tuned signal conveying circuit 8, having a high L/C ratio and comprising a secondary 9 of an intermediate frequency amplifier input transformer 10 and a shunt tuning capacitor 11. The high potential terminal 12 of the tuned input circuit is connected with the grid 6, while the low potential terminal 14 of the tuned input circuit is connected through a by-pass capacitor 15 to ground indicated at 16, which may be the chassis of the apparatus with which the amplifier 5 is associated. 25

The cathode is by-passed to ground by a capacitor indicated at 17 across a self-bias resistor 18, the input capacitance of the tube 5 between the control or input grid 6 and cathode 7 is effectively in shunt across the tuned signal circuit 30 8. A variable biasing potential is applied to the grid 6 from an automatic volume control lead indicated at 20, which in turn receives a negative variable biasing potential responsive to variations in the amplitude of a received carrier 35 wave from a signal rectifier or second detector indicated at 21 through the rectifier output resistor indicated at 22.

The signal rectifier or second detector 21 is coupled to the amplifier 5 to receive amplified signals therefrom, such as a modulated carrier wave, through suitable intermediate amplifying apparatus represented by the rectangle 23, which is coupled to the amplifier 5 through a tuned intermediate frequency interstage transformer indicated at 24 and to the detector 21 through a tuned intermediate frequency output transformer indicated at 25. Automatic volume control potentials for the amplifier 23 are provided through a filter resistor 26 connected with the lead 20, and a similar filter resistor 27 is provided for the amplifier 5. As is well understood, the amplifier 23 may include any suitable number of electric discharge amplifier stages. 40 45 50

The second detector or rectifier 21, is prefer- 55

ably of the diode type having an anode 28 and a cathode 29 connected across the tuned secondary 30 of the intermediate frequency output transformer 25 through the output resistor 22 and a similar output resistor 31 in series therewith between the cathode and the low potential terminal of the secondary 30. The terminal 32 between the resistors 22 and 31 is connected to the chassis or ground, as indicated at 33. Both resistors are suitably by-passed to eliminate the carrier wave, as indicated by the by-pass capacitors 34.

As indicated in the drawings, the cathode terminal 35 of the resistor 31 is made positive, in response to signal flow, while the terminal 36 of the resistor 22 becomes negative, with respect to the grounded terminal 32. If the resistors 22 and 31 are made equal in value, the terminal 35 will become positive at the same rate that the terminal 36 becomes negative and as the signal strength of the carrier wave amplitude increases.

The automatic volume control lead 20 is connected to the terminal 36 to receive an increasing negative biasing potential in response to an increase in signal strength or carrier wave amplitude with respect to chassis or ground 33, thereby to decrease the gain in the amplifiers 5 and 23 as is well understood. Also the modulation component or audio frequency signal may be derived from the output resistor 22 of the detector 21 through an output coupling capacitor 37 and an audio frequency output lead 38.

It should be understood that the audio frequency amplifying portion of the system, as well as the signal input portions of the receiving system connected with the primary 39 of the input transformer 10 are not shown, for the purpose of simplifying the drawings and for the further reason that the present invention is not concerned 40 with such portions of the receiving system.

The input capacitance of the tube 5 varies with variation in the biasing potential provided by the automatic volume control lead 20 in response to signals, and decreases from a fixed value determined by the biasing potential derived from the fixed source 18, which is in series with the variable source 22 between the grid 6 and the cathode 7 and tends to change the tuning of the input circuit 8 of the amplifier. The variation 45 in input capacitance of a typical screen grid pentode amplifier tube, such as the tube 5, and represented by a type known commercially as an RCA 6K7 Radiotron, is shown by the curve 40 in Fig. 2, to which attention is now directed along 55 with Fig. 1.

It will be seen from a consideration of Fig. 2, that the input capacitance decreases rapidly over a short range of biasing potential change, which, for the tube under consideration, may be in the 60 range of from three to ten volts negative, and that this change is substantially linear.

If the control grid of an auxiliary or compensating electric discharge device or tube 39, having a similar relationship between control grid bias 65 and input capacitance to that of the tube 5, is coupled to the tuned high frequency circuit 8, to place its input capacitance across the circuit in parallel with that of the tube 5, by applying a suitable potential to the control grid indicated 70 at 40, the change in input capacitance of the tube 5 may be compensated.

In the practice, as indicated in the drawings, the control grid 41 of the auxiliary or compensating tube 39 may be coupled through a suitable coupling capacitor, indicated at 42, to the high po-

tential terminal 12 of the input circuit 8 and the cathode indicated at 43 may be connected through a suitable self-bias resistor or other fixed bias potential source 44 to ground 45, thereby placing the input capacitance of the tube 39 across the circuit 8. The tube 39 is preferably the same type of tube as that shown at 5, although any suitable tube may be used at 39 to provide a similar relationship to tube 5 between the input capacitance and grid bias variation. 10

Assuming that the tubes have similar characteristics, as shown in Fig. 2, the tube 5 is normally biased to a point A on the curve 40 which corresponds to substantially three volts negative bias, while the compensating grid 41 is biased 15 normally to the point B corresponding to substantially ten volts negative bias. The initial or fixed biasing potentials referred to are supplied by the fixed sources 18 and 44, respectively.

If the signal rectifier output resistors 22 and 31 are made substantially equal and the control grid 41 of the compensating tube 39 is connected through a grid resistor 46 and compensating bias supply lead 47 to the positive terminal 35 of the diode output circuit, the bias potentials with respect to the ground terminal 32 from the rectifier or diode output circuit, in response to a received signal, will become increasingly positive on the grid 41 and increasingly negative on the grid 6 at the same rate, so that the biasing potential 30 indicated at A on curve 40 will increase in a negative direction and that at B will increase in a positive direction, thereby giving substantially no input capacitance change across the circuit 8. 25

If the two tubes are of the same construction, 35 the changes in capacitance may be made substantially equal in magnitude and opposite in direction by applying to the two tubes biasing potentials which vary at equal rates with variations in the strength of an applied signal, and 40 opposite in the direction of the polarity change.

If the tubes 5 and 39 are of different types, the resistors 22 and 31 may be proportioned in accordance with the characteristics of the two tubes so that the input capacitance changes may be 45 made substantially equal and opposite in response to a change in signal strength and a corresponding change in the A. V. C. potential.

With tubes of differing construction for the amplifier and compensating portions of the system, the input capacitance changes may further be adjusted whereby they vary at substantially equal rates and opposite in direction in response to a varying biasing potential, by adjustment of the plate and screen grid voltages applied to the tube 39. In the present example, the screen grid 41 of the tube 39 is connected through a variable contact 48 with a potential source 49 and the anode 50 is connected through an output resistor 51 with a second variable contact 52 in connection with the source 49, whereby the anode and screen grid voltages may be adjusted to provide an input capacitance for the tube 39 to substantially counteract the input capacitance shift of the tube 5. 55

From the foregoing description, it will be seen that, in connection with tuned high frequency circuits, particularly circuits having a high L/C ratio, a variable biasing potential may be applied to the control grids of electric discharge 70 tubes connected with such circuits without permitting the input capacitance changes resulting therefrom to change the resonant frequency of said circuits. In accordance with the invention, this is prevented by causing the mean input ca- 75

5 capacitance across the tuned circuit to be maintained constant or substantially constant between limits which do not appreciably affect the tuning, by a compensating change in the input capacitance between two control grids of electric discharge devices connected with the tuned circuit and signal responsive rectifier means or variable bias means providing output potentials for the two grids which vary in predetermined relation 10 to each other in magnitude and polarity.

15 A specific embodiment comprises a tuned high frequency circuit having the control grid of an electric discharge device connected therewith and automatic volume control means for said device connected with said grid to apply thereto a variable biasing potential. When this potential variation causes the input capacitance to vary between limits affecting the resonant frequency of the circuit, an additional grid connection and a 20 second or additional source of A. V. C. potential which varies with the first A. V. C. potential in an opposite sense is provided. The second source is connected with the second grid and is adjusted for operation to cause the input capacitance 25 changes to be substantially equal and opposite in response to varying signal strength and to maintain the resonant frequency of the circuit substantially constant.

30 If desired, the two control grids may be included in one electric discharge tube or envelope, as shown in the modified circuit of Fig. 3, wherein in the two tubes 39 and 5 are combined in one tube and operated in connection with the same circuit element as in Fig. 1, which bear the same 35 reference numerals as in Fig. 1.

36 Referring to Fig. 3, the tuned input circuit 8 is connected with an amplifier control grid 6 in a common envelope 55 with the compensating control grid 41, the latter being associated with the cathode 43 and the former being associated with the cathode 7. Each of the cathodes is provided with a separate connection to ground 45 and 16 through their respective grid bias resistors 48 and 18. The amplifier output is taken through the output transformer 24 and the positive and negative A. V. C. potentials are applied to the grids 41 and 6 through the leads 47 and 20 from the A. V. C. rectifier output resistors 21 and 22. The grid 41 is operated normally at the point B 45 on the curve 40 of Fig. 2 and the grid 6 is operated normally at the point A on the curve 40 of Fig. 2.

50 In response to received signals, the fixed negative bias potential on the grid 41, as provided by the source 44, is reduced while the fixed negative bias potential on the grid 6, as provided by the source 18, is increased.

55 In the present example, the compensating tube portion of the device 55 is a triode and the anode potential may be adjusted, together with the output resistors 21 and 22, to provide equal and opposite input capacitance change with variation in potential from the A. V. C. rectifier. Otherwise, the operation of the circuit of Fig. 3 is the same as that of Fig. 1.

60 The advantage of the circuit of Fig. 3 lies in the fact that a single tube is required for amplification and compensation, and these functions may be combined in one envelope and require relatively short lead connections to the various elements for both amplification and compensation.

65 I claim as my invention:

1. The combination with a tuned high frequency signal circuit, of an electric discharge device having a control grid and a cathode connected with said circuit providing a predetermined

5 mined input capacitance across said circuit, means for applying a variable biasing potential to said control grid which changes said input capacitance, electric discharge means providing a second control grid and cathode input capacitance across said tuned circuit, and means for causing said last named input capacitance to vary simultaneously with the first named input capacitance in an opposite sense and at a predetermined rate with respect thereto. 10

15 2. The combination with a tuned high frequency signal circuit, of an electric discharge device having a control grid and a cathode connected with said circuit providing a predetermined input capacitance across said circuit, means for applying a variable biasing potential to said control grid which changes said input capacitance, electric discharge means providing a second control grid and cathode input capacitance across said tuned circuit, and means for 20 causing said last named input capacitance to vary simultaneously with the first named input capacitance in an opposite sense and at a predetermined rate with respect thereto, including a connection for said second control grid with said 25 variable biasing means for receiving therefrom a biasing potential which varies at a predetermined rate in magnitude and polarity, with respect to the potential applied to said first named grid. 30

35 3. The combination with a tuned high frequency signal conveying circuit having a high L/C ratio, of electric discharge means providing a predetermined mean input capacitance across said circuit and including two control grids connected with said circuit, means for applying predetermined fixed biasing potentials of differing magnitude to said grids whereby the input capacitance of one grid is reduced and the input capacitance of the other grid is increased with 40 respect to said mean input capacitance, and variable biasing means connected with said grids for causing the input capacitance of said grids to vary at a predetermined rate and in an opposite sense, one with respect to the other, 45 whereby the mean input capacitance across said circuit remains substantially constant. 50

4. The combination with a tuned high frequency signal conveying circuit, of electric discharge means providing a predetermined mean input capacitance across said circuit and including two control grids connected with said circuit, means for applying predetermined fixed biasing potentials of differing magnitude to said grids whereby the input capacitance of one grid is reduced and the input capacitance of the other grid is increased with respect to said mean input capacitance, and means for applying additional biasing potentials to said control grids which vary at predetermined rates and in opposite sense, one with respect to the other. 55

5. In a signal conveying system, the combination with a tuned high frequency circuit, of an electric discharge amplifier device having a control grid connected with said circuit, means for subjecting said grid to a variable gain controlling potential, means for compensating the effect of a change in the input capacitance of said tube comprising a second control grid coupled to said circuit and connected with said first named 70 means to receive therefrom a gain controlling potential of opposite polarity which varies in magnitude with the first named potential, said first named means including signal rectifier circuit elements for maintaining a predetermined 75

- relation between the magnitude and rate of change of said potentials and the input capacitance changes provided by said grids substantially equal and opposite.
6. The combination with a tuned high frequency signal conveying circuit, of electric discharge means providing a predetermined mean input capacitance across said circuit and including two control grids connected with said circuits, 5 means for applying predetermined fixed biasing potentials of differing magnitude to said grids whereby the input capacitance of one grid is reduced and the input capacitance of the other grid is increased with respect to said mean input 10 capacitance, and means for causing the said input capacitance of said grids to vary at a predetermined rate and in an opposite sense, one with respect to the other, whereby said mean input capacitance across said circuit remains substantially constant, said last named means comprising a source of negative biasing potential for one of said grids and a source of positive bias potential for the other of said grids conjointly variable to cause said potentials to increase and 15 decrease simultaneously at predetermined rates, one with respect to the other.
7. In a signaling system, the combination with a tuned high frequency signal conveying circuit of an electric discharge device having a first control grid connected with said circuit providing a predetermined input capacitance for said circuit, a second control grid providing a predetermined compensating input capacitance for said circuit, and means providing a change in the input 20 capacitance provided by one grid substantially equal in magnitude and opposite in direction to changes in the input capacitance provided by the other of said grids in response to variations in grid bias applied to said grids, said last named means comprising a grid bias potential supply circuit connected to each of said grids and a variable potential source connected with said circuits and providing potentials of opposite polarity on said grid bias potential supply circuits 25 and a predetermined rate of change of magnitude for said potentials, one with respect to the other.
8. In an electric discharge amplifier, the combination with a tuned high frequency circuit, of an electric discharge amplifier device having a control grid and a cathode connection providing input capacitance across said circuit, means for adjusting said input capacitance to a predetermined value, means including a second control grid and cathode connection for said circuit and 30 a second input capacitance across said circuit, means for adjusting said last named input capacitance to a predetermined value differing from the first named input capacitance, means for applying variable biasing potentials to said control grids to vary the gain of said amplifier and for causing said input capacitances to vary at predetermined rates and in an opposite sense, one with respect to the other.
9. The combination with a tuned high frequency signal conveying circuit, of electric discharge means providing a predetermined mean input capacitance across said circuit and including two control grids connected with said circuits, 35 means for applying predetermined fixed biasing potentials of differing magnitude to said grids whereby the input capacitance of one grid is reduced and the input capacitance of the other grid is increased with respect to said mean input capacitance, and means for applying additional biasing potentials to said control grids which vary at a predetermined rate and in opposite sense, one with respect to the other, said last named means comprising a signal rectifier for receiving an applied signal, an output resistor 40 for said rectifier having a positive terminal connected with one of said control grids, a negative terminal connected with the other of said control grids and a tap intermediate between said terminals providing a cathode connection.
10. In an electric signalling system, the combination with a tuned signal transmitting circuit, of an electric discharge device having a control grid connected with said circuit and providing input capacitance across said tuned circuit variable with variations in grid bias, means for applying to said control grid a variable biasing potential, and electric discharge means for preventing the tuning of said circuit from varying 45 in response to variations in said input capacitance, said last-named means including a second control grid coupled to said input circuit to provide a second variable input capacitance across said circuit, and means jointly operable with said first-named grid bias means for applying to said second grid a biasing potential which varies in an opposite sense from the variations in the biasing potential on the first-named grid and so proportioned with respect thereto that said input capacitance variations on 50 said tuned circuit may be made substantially equal and opposite.

RICHARD M. STEERE.
